GARMENT STEAMER

Carl R. Lendle, Youngstown, Ohio, assignor to
 United States Hoffman Machinery Corporation,
 New York, N. Y., a corporation of Delaware

Application December 3, 1943, Serial No. 512,755

13 Claims. (Cl. 223—70)

1

My invention relates to the cleaning and renovating of garments, and has among its objects and advantages the provision of an improved garment steamer embodying novel means for adjusting the device to the size and contour of the garments, particularly with respect to shoulder, waist and hip line contours.

In the accompanying drawings:

Figure 1 is a side view of the garment steamer.

Figure 2 is a sectional view along the line 2—2 of Figure 1.

Figure 3 is a sectional detail view of the neck and shoulder structure of the steamer.

Figure 4 is a sectional detail view of a latching device.

Figure 5 is a horizontal sectional view through the shoulder structure illustrating the device in its fully extended position.

Figure 6 is a similar view but illustrating the shoulder structure adjusted to garments of smaller shoulder sizes.

Figure 7 is a sectional detail view of a resilient side structure of the garment steamer.

Figure 8 is a side view of a modified form.

Figure 9 is a sectional view taken along the line 3—9 of Figure 8.

Figure 10 is a vertical sectional view of the garment steamer of Figure 8 rotated 90 degrees.

Figure 11 is a view in side elevation of the upper portion of the form showing the collar shaper.

Figure 12 is a view in front elevation of the form as shown in Figure 11, and

Figure 13 is a view similar to the upper portion of Figure 8 showing the means for heating the pads electrically.

In the embodiment of the invention selected for illustration, I make use of an annular base 10 arranged upright and provided with a top wall 12 of slightly dished contour. This wall is provided with a flange 14 welded to the inner face of the base. Located centrally of the wall 12 is a steam chamber 16 provided with a row of openings 18. Steam is admitted to the chamber 16 through the medium of a pipe 20.

Upon the steam chamber 16 is fixedly mounted a heater 22 which receives steam from a pipe 24 extending vertically through the top 12 and the steam chamber 16.

A form 26 is mounted on the heater 22, which form includes an annular flange 28 to which is attached a spider 30 provided with a bearing 32 resting on a bearing pin 34 attached to the upper end of the heater 22. This pin extends loosely in a guide socket 36 depending from the spider 30 to hold the pin in alignment with the bearing

2

32, thus the form 26 may be rotated about a vertical axis on the pin 34.

The form 26 comprises an upper section 38 and a lower section 40. The flange 28 comprises a fixed part with the section 40, and the latter is provided with a bottom flange 42 which carries an end wall 44. This end wall is provided with a centrally located neck 46 arranged loosely on the steam chamber 16. A sealing ring 48 is supported in engagement with the bottom end of the neck 46 by an annular flange 50 attached to the steam chamber 16.

Arms 52 are welded to the bottom 44 and project horizontally to support a table 54 of slightly larger diameter than the base 10 and provided with a depending flange 56. This table comprises a fixed part with the section 40.

A steam duct 58 is arranged vertically on the end wall 44 and concentrically of the heater 22. This duct is of considerably larger diameter than the heater 22 and is open at its upper end. This duct facilitates the rapid delivery of steam to the section 38 in cases where the garments are draped on that section only. When, however, full length garments are draped on the steamer, steam is admitted to both sections 38 and 40, the steam being admitted to the section 40 through the medium of ports 60 in the lower end margin of the duct 58. A band 62 encircles the lower end margin of the duct 58, and is arranged between a retaining flange 64 and the end wall 44, but the band may be rotated relatively to the steam duct. This band is provided with ports 66 equal in number to the ports 60. The ports 60 may be fully or partly opened through adjustment of the band 62, the latter being provided with a handle 68 extending through a slot 70 in the section 40. When the ports 60 are partly or fully opened, steam is admitted to the lower end of the section 40, and steam also passes upwardly through the duct 58.

A hinge 72 connects the sections 38 and 40, the hinge being attached to the flange 28 and a similar flange 74 at the bottom end of the section 38. Both sections are pervious to steam. Normally the section 38 rests on the section 40 in the position of Figure 2. However, the section 38 may be swung downwardly, which lends access interiorly to both sections.

The section 40 comprises a metallic mesh wall 76 covered exteriorly by a canvas 78. The section 38 comprises an inner metallic mesh body 80 attached to the flange 74 at its lower end and to a hollow body 82 at its upper end. The body 80 extends above the body 82 and is shaped to pro-

vide a neck and partial shoulder contour 84. Figures 5 and 6 illustrate the cross sectional contour of the body 80, which body is covered exteriorly by canvas 86. This canvas lies snugly to the front and rear faces of the body 82, but includes considerable slack along its side edges, as indicated at 88.

To the lower end and at each side of the body 80 is hingedly connected a metallic mesh panel 90, as at 91. The two panels comprise sections 92 and 94 of substantially equal lengths, the two sections on the two sides being hingedly connected together at 96. The slack portions 88 of the canvas 86 are attached to the panels 90 throughout substantially their entire lengths. Padding 98 is interposed between the slack portions 88 and the upper end margins of the panels 90 to provide a garment shoulder contour of gentle curvature.

Normally the panels 90 take the positions of Figure 2, which positions are yieldingly maintained by compression springs 100 and 102 respectively supported in sockets 104 attached to the body 80. The outer ends of the springs are attached to the panels.

Latch bars 106 are hingedly connected at 108 with the respective sections 94, which bars lie in the channel 110 of the body 82. Both latch bars are provided with openings 112 for selectively receiving hooks 114. These hooks are pivoted at 116 to a plate 118 attached to the channel 110, and the hooks are balanced to lie at rest on the bars 106 and to fall into the notches 112 as the bars 106 are pressed inwardly through the application of pressure on the panels 90. The springs 100 and 102 offer little resistance to such adjustment of the panels, the resistance being such that the panels may be moved inwardly through garment pressure when the garment is pulled over the shoulder structure of the form. However, the panels 90 may be adjusted to desired positions before the garment is draped on the form, and the hooks 114 will engage in openings 112 to latch the bars 106 against outward movement to hold the panels 90 in the desired positions.

In Figure 4, an eccentric 120 is attached to a shaft 122 rotatably journaled in the plate 118 and a bearing 121 attached to the body 80. When the eccentric 120 is positioned in accordance with Figure 4, the hooks 114 lie clear of the bars 106. Means for rotating the eccentric 120 comprises a link 124 pivotally connected at one end with an arm 126 attached to the shaft 122. The other end of the link is pivotally connected with an arm 128 fixed to a shaft 130 rotatably supported in a bearing 132 attached to the body 80. The other end of the shaft 130 extends through an opening 134 in the body 80 and is provided with a handle 136 to facilitate rotation thereof.

A quick opening valve 138 is interposed in the pipe 20, which pipe has communication with the upper end of a chamber 140. This chamber is provided with a steam inlet pipe 142 communicating with a steam generator (not shown). A drain pipe 144 communicates with the chamber 140, and the pipe 24 has communication with this drain pipe. Condensate forming in the chamber 140 may be drained therefrom through the pipe 144. A steam outlet pipe 146 leads into the heater 22, and a pipe 148 communicates with the steam chamber 16 and is connected with a suction device (not shown). This suction pipe is provided with a foot operated valve 150.

The section 38 when adjusted according to Fig-

ure 2 accommodates large garments. There are three openings 112 in each bar 106, so that the section 38 may be adjusted to accommodate garments of large, medium and small sizes. Conventional wooden sleeve forms are employed in shaping the garment sleeve during the steaming process.

The body 80 is provided with a transverse wall 152 provided with openings 154 to permit passage of steam into the body above the partition. A large vertical duct 156 opens through the partition 152 and is fixedly secured thereto and to the body 82. However, the upper end of the duct 156 is closed. Branch ducts 158 communicate with the duct 156 and open through the body 80 near its upper end for the admission of steam to the shoulder regions of the form, particularly between the upper end of the body 80 and the slack portions 88. While the sections 38 and 40 permit passage of steam therethrough throughout their entire areas, which is also true of the slack portions 88 and their associated panels 90, the duct 58 and its ports 60 together with the ducts 156 and 158 and the ports 154 function to provide an efficient distribution of steam throughout the entire form structure.

The form 26 is provided at its lateral sides with extension members 25 which extend from the waist to the bottom of the form. The extension members 25 are hinged at their upper ends, as at 27, to the waist of the form 26. The extension members 25 are adjustable laterally outward with relation to the form 26 to increase the effective width of the skirt portion 49 of the form and thus adapt it to fill out or expand the skirt part of a bell-shaped coat, whereby to enable such garment to be efficiently cleaned. The extension members 25 are adjusted outwardly to the required extent through the medium of handles 27a which are secured to the lower ends of the extension members and which extend laterally outward from the said members. Bars 29 carried by the lower ends of the extension members 25, and having a snug sliding fit in collars 31 fixed to the flange 42 at the bottom of the form 26, provide means for maintaining the extension members in their adjusted position. The extension members 25 conform transversely and longitudinally to the lower or skirt section 40 of the form 26 to permit them to lie in close conforming relation to the form when in their innermost position.

As shown in Figures 11 and 12, the form 26 may be, and preferably is, provided with a collar shaper 33 which is associated with the neck 35 of the form and which is curved to fit the back and sides of the neck. The collar shaper 33 is made of a strip of flat metal and is covered with a suitable padding and canvas to prevent it from leaving an impression on the collar of the garment. The collar shaper 33 is supported by a curved arm 37 from a bracket 39 fixed, as at 41, to and extending upwardly and forwardly from the neck of the form 26. The arm 37 is pivoted at one end, as at 43, to the upper end of the bracket 39. The collar shaper 33 is fixed rigidly, as at 45, to the other end of the arm 37. Coil springs 47 fixed, as at 49, to the bracket 39 and, as at 51, to the arm 37, functions to maintain the collar shaper in its lower or operative position or in its raised or inoperative position, as shown by solid and dotted lines, respectively, in Figure 11. When the collar shaper 33 is in inoperative position, the arm 37 rests against a stop pin 53 carried by and extending upwardly and forwardly from the base of the bracket 39. The springs 47

also impart a slight pressure to the collar shaper 33, whereby to press the collar while the garment is being steamed.

After steaming of the garment, the garment is dried by opening the suction pipe 148.

Figures 8 through 10 illustrate a modified construction primarily designed for servicing garments of the sack coat type. This device includes a single metallic mesh body 160 provided with a transverse spider 162 having a bearing 164 resting on the upper end of a rod 166 attached to cross arms 168 secured to a neck 170 comprising the upper end of a base or housing 172.

A band 174 encircles the lower end of the form 160 and has arms 176 attached thereto and provided with an opening 178 rotatably receiving the rod 166 which balances the body on the rod. This band closely embraces the neck 170.

The base 10 is provided with a dome-shaped spider 180 upon which is mounted a finned heating coil 182 having communication with a steam inlet pipe 184. This pipe enters one end of the coil 182, and the other end of the coil communicates with a steam outlet pipe 186. Means for delivering steam to the body 160 comprises a circular tube 188 having perforations 190 extending upwardly and concentrically of the neck 170. This tube is provided with a steam inlet pipe 192.

The body 160 is provided with a canvas cover 194 provided with slack portions 196 along the sides of the body. Mesh panels 198 are arranged inside the slack portions 196 and are reinforced by metal bars 200. There are two vertical bars 200 for each panel 198 and the two bars on each side are hingedly connected together at 202. The panels 198 are yieldingly held in the positions of Figure 10 by means of compression springs 204, one such spring engaging each bar 200. These springs are seated in sockets 206 attached to the body 160, with the outer ends of the springs attached to the respective bars 200.

To the upper ends of the two uppermost bars 200 are hingedly connected bars 208 which slidably rest on a partition 210 attached to the body 160. A chain 212 connects with each bar 208, and the chains pass over grooved wheels 214 mounted on the partition 210. These two chains are connected as a unit to provide a single pull chain 216 passing around a grooved wheel 218 mounted on the band 174. An opening 220 is provided in the band 174 for connection with a lever 222 pivotally mounted on a bracket 224, also attached to the band 174.

In Figure 9, the bracket 224 is provided with a series of openings 226 for the reception of a latch formation on the lever 222 to releasably latch the lever in different positions. Thus the shoulder contour of the form may be varied through adjustment of the lever 222.

The lower ends of the two lowermost bars 200 are hingedly connected with bars 228 which are slidably mounted on two of the cross arms 176. Chains 230 connect with the bars 228 and pass over grooved wheels 232 mounted on the body 160. These two chains are connected as a single chain 234 which passes around a grooved wheel 236 attached to the band 174. This chain passes through a slot 238 in the band 174 and connects with a lever 240 identical with the lever 222.

A fan 242 is arranged inside the base 172 for rotation about a vertical axis. This fan is driven by a motor 244. The base 172 is provided with screened openings 246 for the inlet of air.

The amount of air blown into the form is con-

trolled by plates 248 arranged in parallel relation and pivotally mounted on shafts 250. The other ends of the plates are pivotally connected with a bar 252, this bar being provided with an actuating lever 254 which extends through an opening 256 in the base 172. Notches 258 are provided in the lever 254 to engage over a lip 260 attached to the base, so that the lever may be latched in different positions to vary the spacing between the plates 248.

A table 262 is attached to the base 172.

As shown in Figures 8 and 13, that form of the apparatus designed for servicing garments of the sack-coat type is provided with front and rear pressing pads 268 and 270. These pads are mounted on brackets 264 and 266 carried by the band 174, the pads being connected to the brackets by means adapted to permit the pads to be moved away from the body 160 when a garment is being placed on or removed from the body. The pad 268 is mounted upon its bracket 264 by means comprising an upright bar 265 which is mounted at its lower end on the bracket. This means also comprises arms 265a by which the pad is mounted on the bar, the arms being pivoted to the pad, as at 265b, and to the upper and lower ends of the bar. The pad 268 is held under pressure against the front side of the body 160 by a spring pressed latch 265c which is mounted, in an operative manner on the band 174 and which when in operative position contacts with the front side of the lower arm 265a, as shown in Figure 8. The bracket 264 extends laterally and forwardly from the band 174. This together with the manner in which the pad 268 is mounted upon the bracket, permits the pad to be swung to one side of the body 160 as shown by broken lines in Figure 8. The pad 270 is connected to its bracket 266 by means comprising an arm 266a and a link 266b, the arm being fixed rigidly to and extending rearwardly from the pad, and the link being pivoted to the arm and bracket. The pad 270 is held under pressure against the lower portion of the rear side of the body 160 by springs 266c. The retracted position of this pad is shown by dotted lines in Figure 8.

Each of the pads 268 and 270 comprise frames 268a and 270a and canvas covers 268b and 270b which are secured on the frames by lacings 268c and 270c.

The pads hold the coat in position on the body or form 160 and at the same time press the coat. The canvas of the pads is stretched over the frames, and it may, should it shrink through steaming, be loosened to shape itself over the form by loosening the lacings.

If desired the pads may be heated by steam or electricity. To adapt them to be heated by steam a coil or pipe is arranged within each and connected to a suitable source of steam supply. The manner in which the pads are electrically heated is shown in Figure 13. This heating means comprises resistance elements 269 arranged between layers of insulating material 269a. The resistance elements 269 are supplied with current from contact rings 269b located between the band 174 and connected to a suitable source of current. The rings 269b have a fixed position and the form or body 160 may turn with respect thereto. The resistance elements 269 are connected to the rings 269b by conductors 269c which are connected to wipers 269d mounted on and insulated from the ring 174 and having a sliding contact with the rings. The means for

insulating the parts 269a on the ring 174 consists of a block of insulating material 269e.

The pipes 184 and 192 communicate with the chamber 272 having a steam inlet pipe 274 communicating therewith and adapted for connection with a steam generator (not shown). Both pipes 184 and 192 communicate with the upper end of the chamber 272, while the pipe 186 connects with the bottom end of the chamber, as with a condensate bleed line 276.

In both forms of the device, the devices are adjustable to accommodate garments of different sizes. The forms may be latched in different positions to accommodate garments of particular sizes, which relieves form pressure on the garments. Thus the garments are subjected only to steam pressure for contouring purposes, and the latching features eliminate excessive form pressure on the garments. Excessive form pressure during the steaming operation is objectionable in that it causes stretching of the garments.

All the mesh bodies are of substantial construction so as to maintain their contour in addition to carrying structural parts which are attached thereto.

Without further elaboration, the foregoing will so fully explain my invention, that others may, by applying current knowledge, readily adapt the same for use under various conditions of service.

I claim:

1. A garment steamer form comprising a hollow body pervious to steam having integral immovable side portions, a steam pervious flexible covering on said body and having slack portions disposed adjacent said side portions, steam pervious panels attached to the interior of said slack portions, and resilient means normally urging said panels outwardly from said body.

2. A garment steamer form comprising a hollow body pervious to steam having integral immovable side portions, a steam pervious flexible covering on said body and having slack portions disposed adjacent said side portions, steam pervious panels attached to the interior of said slack portions, resilient means normally urging said panels outwardly from said body, and means for latching said panels in different positions.

3. A garment steamer form comprising a hollow body pervious to steam having integral immovable side portions, a steam pervious flexible covering on said body and having slack portions disposed adjacent said side portions, steam pervious panels attached to the interior of said slack portions, resilient means normally urging said panels outwardly from said body, said panels having pivotally connected parts, and means for latching the panels in different positions corresponding to particular garment sizes.

4. The invention described in claim 1 wherein means are provided for admitting steam to the interior of said hollow body and means for conducting steam freely from the interior of said body into the space inside said slack portions of said flexible covering.

5. The invention described in claim 1 wherein said form includes upper and lower sections, with said panels and said slack portions associated with said upper section, and means for distributing steam to both sections.

6. The invention described in claim 1 wherein a heater is mounted inside said form, a steam duct arranged about said heater and having an open upper end, means for controlling the passage of steam from said duct at its lower end, a

second steam duct located at the upper end of said form in axial alignment with said first mentioned steam duct and steam duct branches placing said second steam duct in communication with the interior of said slack portions of said flexible covering.

7. The invention described in claim 1 wherein said panels are pivotally connected with said form at the bottom end of the form, said panels comprising hingedly connected sections, and means for latching said panels in different positions with respect to said body to vary the garment size of the form.

8. The invention described in claim 1 wherein said panels comprise pivoted sections, a first lever operated pull line means connected with certain of said sections to adjust one end of the panels relatively to said body, and lever actuated pull lines connected with the other sections to adjust the other ends of said panels relatively to said body.

9. A garment steamer comprising a hollow body pervious to steam, extension members at the lateral sides of the body extending from the waist to the bottom of the body, means pivoting the upper ends of the extension members to the body for lateral adjustment with relation to the body, collars fixed to the bottom of the body, and rods carried by the lower ends of the extension members and having a snug sliding fit in the collars, said collars and rods constituting means for securing the extension members in their adjusted position.

10. A garment steamer comprising a hollow body pervious to steam and having a neck portion, a collar shaper embracing the back and sides of the neck portion, means pivotally mounting the collar shaper on the body, and means yieldingly urging the collar shaper in the direction of the neck portion of the body.

11. A garment steamer comprising a hollow body pervious to steam and having a neck portion, a collar shaper embracing the back and sides of the neck portion, means pivotally mounting the collar shaper on the neck portion for movement into lowered or operative position or into raised or inoperative position, and spring means associated with said first means for maintaining the collar shaper in either of said positions.

12. A garment steamer comprising a hollow body pervious to steam and having a neck portion, a collar shaper embracing the back and sides of the neck portion, a bracket secured to and extending upwardly from the neck portion, a stop pin carried by the bracket, a rearwardly and downwardly curved arm carrying the collar shaper and pivoted to the bracket to enable the collar shaper to be moved into operative or inoperative positions, the arm resting against the stop pin when the collar is in inoperative position, and spring means connected to the bracket and to the arm to hold the collar shaper in either of said positions.

13. A garment steamer comprising a body provided with a neck portion, a collar shaper embracing the back and sides of the neck portion, means mounting the collar shaper on the body for movement with relation to the neck portion, and resilient means urging the collar shaper in the direction of the neck portion.
